(57) **CLAIM**

The ornamental design for a table, as shown and described.

DESCRIPTION

FIG. 1 is a left front perspective view of a table showing my new design;

FIG. 2 is a side elevational view, the opposite side being a mirror image thereof;

FIG. 3 is an end elevational view, the opposite end being a mirror image thereof;

FIG. 4 is a top view thereof;

FIG. 5 is a left front perspective view of a second embodiment of a table showing my new design;

FIG. 6 is a top view of the table in FIG. 5; and,

FIG. 7 is an end elevational view of the table in FIG. 5, the opposite end being a mirror image thereof.

The views not shown are not claimed and form no part of the claimed design.
